UNITED STATES PATENT OFFICE.

LÁZARO DE LA GARZA, OF TORREON, MEXICO.

DESIGN FOR AN ARTICLE OF MANUFACTURE.

47,033.

Specification for Design.

Patented Mar. 2, 1915.

Application filed October 14, 1914. Serial No. 866,719. Term of patent 3½ years.

To all whom it may concern:

Be it known that I, LÁZARO DE LA GARZA, a citizen of the Republic of Mexico, residing at Torreon, in State of Coahuila, Mexico, have invented a new, original, and ornamental Design for an Article of Manufacture, of which the following is a specification, reference being had to the accompanying drawing, forming part thereof.

The figure is a plan view of a sheet of paper, showing my new design.

I claim:

The ornamental design for an article of manufacture, as shown.

LÁZARO DE LA GARZA.
